UNITED STATES PATENT OFFICE.

CHARLES E. DOLAN, OF NEWARK, NEW JERSEY.

LID-LIFTER.

1,193,369.

Specification of Letters Patent. Patented Aug. 1, 1916.

Application filed August 20, 1915. Serial No. 46,533.

To all whom it may concern:

Be it known that I, CHARLES E. DOLAN, a citizen of the United States, residing at Newark, in the county of Essex and State 5 of New Jersey, have invented certain new and useful Improvements in Lid-Lifters, of which the following is a specification.

This invention relates to lid lifters more particularly adapted for use with domestic 10 cooking vessels, and is especially designed with a view toward constructing a useful article, cheap to manufacture and convenient to operate.

The primary object of the invention is 15 to provide a device of the character set forth which shall have a positive gripping action upon the knob of the lid to be lifted and to also provide means for supporting the device in position to give the proper 20 leverage.

A further object of this invention is to provide a lid lifter which shall be constructed of wire bent to form the complete device.

25 With these and other objects in view as will hereinafter appear, this invention consists in the combination and construction of the various related parts and elements of a lid lifter as hereinafter described and more 30 particularly set forth in the appended claim.

Referring to the accompanying drawings, forming a portion of this specification and illustrating the preferred embodiment of 35 the invention and in which similar reference characters indicate similar parts wherever used:—Figure 1 is a perspective view showing the use of the device. Fig. 2 is a fragmentary top plan view of the device; 40 and Fig. 3 is a side elevation of a portion of the device.

Two strands of wire 4 and 5 are twisted together to form a handle 6, bent around at 7, and converging at 8 and 9, where the 45 strand 5 is crossed and bent to form projections 10, 11, extending rearwardly and parallel to the handle 6, and having small bends 12, 13 therein in order to give the proper angle to the projections 10, 11.

50 The strand 4, from the points 14, 14, is

bent outwardly at 15, 16, to bends 17, 18, from which extend straight portions 19, 20.

The use of the device is as follows: The device is grasped by means of the handle 6, and the knob 21 of the pan lid 22 engaged 55 between the members 19 and held between the bent portions 17, 18, the projections 10, 11, bearing upon the pan lid 22, serving to support the device in position to lift the lid.

In order to prevent spreading at the points 14, 14, a ring 23 of wire is bent around all four wires 4, 4 and 5, 5.

It will be obvious that my invention is susceptible of some change and modification 65 without material departure from the principles and spirit thereof and for this reason I do not wish to be understood as limiting myself to the precise arrangement and formation of the several parts herein shown, 70 but to construe the claim as broadly as the state of the prior art will permit.

What I claim is:—

A lid lifter comprising a piece of wire 75 bent about midway of its length to form two legs brought substantially together near the free ends, the legs beyond the point where they are brought together forming part of a handle and the other portion of the bent wire beyond where they are brought 80 together being spread apart to provide a pair of spaced fingers, each of said fingers being bent outwardly intermediate its length to form with the bent portion of the companion finger a seat for the knob of a vessel top, a second wire bent intermediate its 85 length to correspond with and twisted with the first mentioned wire from the point where the legs of the latter are brought together, the twisted portions of the two wires 90 forming a handle reinforced throughout its length, one free end of the second mentioned wire being bent laterally across the opposite finger of the first mentioned wire and is then bent rearwardly and terminating in a 95 lateral leg, the other free end of the second mentioned wire being bent across the other opposite finger of the first mentioned wire and the before mentioned lateral leg and bent rearwardly and terminating in a sec- 100

ond lateral leg and a tie wire engaging the first and second mentioned wires between the beginning of the twisted part and the bent lateral legs, the tie wire serving to lock 5 the handle's legs together to prevent spreading to form a rigid structure.

In testimony whereof I affix my signature in presence of two witnesses.

CHARLES E. DOLAN.
